COMB FOR CARDING MACHINES

Alexander Cavedon, Woonsocket, R. I.

Application May 20, 1940, Serial No. 336,115

3 Claims. (Cl. 19—106)

The present invention relates to doffer combs for carding machines, and has for its object to provide an improved mechanism for moving a comb in a straight line, substantially tangential to the periphery of a doffer roll.

In prior devices of this character combs have been mounted for oscillatory movement about an axis considerably spaced from the point where the fibre web is stripped from the periphery of the doffer roll. Such spacing is necessary in order that the comb will travel through an arc having a large radius, with the result that the doffed web must travel a considerable distance without support, before entering between the feed rolls of a condenser, or other device for operating on the web.

According to the present invention, there is provided an improved mounting and operating mechanism for a doffer comb, whereby a rectilinear movement is imparted to the comb, in a direction that is always substantially tangential to the periphery of the doffer roll. As a result, the mounting for the comb is close to the periphery of the doffer roll, so that the web has only a short distance to travel before entering the rolls of the condenser or other associated device. Furthermore, the comb is so mounted that it may be closely adjusted with respect to the periphery of the doffer roll, without affecting the tangential direction of its reciprocatory movement.

The above and other advantageous features of the invention will hereinafter more fully appear, from the following description considered in connection with the accompanying drawing, in which:

Fig. 1 is a view in side elevation of a portion of a doffer roll having a comb mechanism co-operating therewith, in accordance with the present invention.

Fig. 2 is a plan view of a portion of the parts shown in Fig. 1.

Fig. 3 is a fragmentary sectional view, along the line 3—3 of Fig. 2.

Fig. 4 is a view in front elevation of the assembled parts of the comb operating mechanism removed from the doffer roll.

Fig. 5 is a fragmentary sectional view along the line 5—5 of Fig. 4, and illustrating adjustment of the comb relative to the doffer roll.

Referring to the drawing, the comb structure of the present invention is shown in connection with a portion of a carding machine having a doffer roll 1, from which a fibre web 2 is stripped by a comb 3 having a straight line movement, as

later described. Beyond the comb 3, and very close to the point where the web is stripped from the doffer roll, there is shown a pair of opposed web receiving rolls 4, such, for example, as the dividing rolls of a condenser for operating on the stripped web, in the usual manner. The position of these rolls 4 illustrates their extremely close relation to periphery of the doffer roll 1, which is made possible by my improved comb support, and which relation would not be possible with the conventional type of comb mounted for oscillatory movement about an axis.

A portion of the frame of the carding machine is indicated at F, and as shown in Fig. 4, brackets 5 are mounted on this frame at each end of the doffer roll 1, for supporting between them a pair of supports 6 for the comb assembly. The supports 6 are secured to the brackets 5 by means of bolts 7, and each support has an arcuate slot 8 therein for receiving one of the bolts 7, thereby making it possible to adjust the entire comb assembly with respect to the periphery of the doffer roll, as will later appear.

As best shown in Figs. 2 and 4, each support 6 provides a vertical slot 9, in which is received a plunger 10, with the upper ends of the plungers 10 providing inwardly extending projections 11 terminating in arms 12 extending downwardly between the supports. The arms 12 are connected by a horizontal bar 13, to which the comb 3 is attached, so that movement of the plungers 10 in the supports 6 will impart straight line movement to the comb 3, in a direction substantially tangential to the periphery of the doffer roll 1, as best shown in Fig. 5.

It is to be noted that the cross bar 13 carrying the comb 3 is movable as a unit with the plungers 10 and their connected arms 12, so that the comb 3 always moves in a straight line determined by the parallel relation between the plungers 10.

Referring again to Fig. 1, each support 6 has mounted thereon a bracket 14 and the opposite brackets 14 support a horizontally extending shaft 15. Adjacent the ends of this shaft are positioned gear segments 16 meshing with rack teeth 17 on the plungers 10. A depending arm 18 on the shaft 15 has attached thereto one end of a connecting rod 19, the other end of which is connected by a pin 19a on a crank disk 20 turnable with a pulley 21 journaled on a stud 22 on one of the supports 6. A suitable belt 23 drives the pulley 21, and thereby causes oscillation of the gear segments 16 to impart a vertical reciprocatory movement to the plungers 10,

in unison. The connection between the arm 18 and the connecting rod 19 is preferably adjustable by means of a slot 24 in the arm, to control the extent of the comb travel. In operation it has been found that the gear segments 16 are adapted to impart a reciprocatory movement to the plungers 10 and the comb assembly supported therebetween, without any substantial vibration being imparted to the comb as might otherwise occur with a direct driving connection to the comb bar.

By the arrangement shown, the comb 3 is given a vertical reciprocatory movement substantially tangential to the periphery of the doffer roll 1, and the length of the reciprocatory movement may be varied by adjustment of the connecting rod 19 and arm 18. Moreover, by angular adjustment of the supports 6 about the bolts 7 opposite to the slots 8, the spacing of the operative edge of the comb 3 from the periphery of the doffer roll 1 may be closely adjusted to suit different conditions of operation, as indicated in dotted lines in Fig. 5. It will be also noted that the mounting for the comb is such that lint or dust from the material passing through the carding machine will not interfere with the proper functioning of the mechanism. In addition, the comb supporting and reciprocating mechanism is so located that it does not interfere with the positioning of other mechanism very close to the doffer roll.

I claim:

1. In a carding machine having a doffer roll, a bracket positioned adjacent each end of the roll, a support adjustably mounted on each bracket, each support having a substantially vertical guide therein, a plunger positioned in each

guide, a comb extending between the supports and having upwardly extending projections on opposite ends thereof, means for connecting each of the projections to the adjacent plunger adjacent the top thereof, and means acting directly on said plungers for reciprocating them in unison.

2. In a carding machine having a doffer roll, a bracket positioned adjacent each end of the roll, a support adjustably mounted on each bracket, each support having a substantially vertical guide therein, a plunger positioned in each guide, a comb extending between the supports and having upwardly extending projections on opposite ends thereof, means for connecting each of the projections to the adjacent plunger adjacent the top thereof, and means for reciprocating the plungers in unison, said last means including a pair of gear segments, and means for oscillating said gear segments simultaneously, each of said plungers having teeth thereon engageable by the gear segments.

3. A combing device for the doffer roll of a carding machine comprising in combination spaced supports positioned adjacent the ends of said roll, with each support having a straight guideway therein, plungers movable in said guideways, with the horizontally aligned ends of said plungers supporting between them a comb bar carrying a comb having its teeth adjacent the periphery of said doffer roll, a shaft extending between said supports carrying operating members engaged with said plungers, and means for imparting oscillatory movement to said shaft which is converted into straight line movement of said plungers by said operating members.

ALEXANDER CAVEDON.
